UNITED STATES PATENT OFFICE.

WILLIAM H. V. SHRUM, OF COLUMBUS, OHIO.

DESIGN FOR A FLYING TOY.

56,772.

Specification for Design.

Patented Dec. 14, 1920.

Application filed June 9, 1920. Serial No. 387,757. Term of patent 3½ years.

To all whom it may concern:

Be it known that I, WILLIAM H. V. SHRUM, a citizen of the United States, residing at Columbus, in the county of Franklin and State of Ohio, have invented a new, original, and ornamental Design for Flying Toys, of which the following is a specification, reference being had to the accompanying drawing, forming a part thereof.

The figure is a perspective view of a flying toy, showing my new design.

I claim:

The ornamental design for a flying toy as shown.

WILLIAM H. V. SHRUM.
